STEM FOR INCANDESCENT LAMPS AND METHOD OF MAKING

Filed March 25, 1922

FIG. 1.

FIG. 2.

FIG. 3.

INVENTOR
JOHN J. HIGGINS

BY
J. J. Higgins
ATTORNEY

Patented May 3, 1927.

UNITED STATES PATENT OFFICE.

JOHN JOSEPH HIGGINS, OF EAST ORANGE, NEW JERSEY, ASSIGNOR TO WESTING-
HOUSE LAMP COMPANY, A CORPORATION OF PENNSYLVANIA.

STEM FOR INCANDESCENT LAMPS AND METHOD OF MAKING.

Application filed March 25, 1922. Serial No. 546,679.

This invention relates to incandescent lamps and their manufacture and more particularly to the stem used with the type known as the tipless lamp, although my invention may also be employed in a tipped lamp.

An object of my invention is the provision of a method for the manufacture of stems for incandescent lamps and other electrical devices including a sealed container whereby the cost of their production is reduced.

Another object of my invention is the provision of a stem for a tipless incandescent lamp comprising a less number of parts than those heretofore used, certain of which parts perform additional functions.

A further object of my invention is the provision of a stem of rugged construction composed of few parts and made in such a manner that cooling strains and other sources of shrinkage are lessened.

Other objects and advantages of the invention will be apparent as the description proceeds.

25 Stems for lamps of the tipless construction are at present made by placing the flare in a stem-making machine, inserting an inner or exhaust tube therein with the leading-in wires therebetween and, after softening the glass in the usual manner by heat, the flare, the inner tube and the wires are consolidated by the application of clamping jaws or other mechanical pressing means. 30 This method weakens the stem to a considerable extent by elongation or flattening the same at the press by the usual clamping jaws, which also chills the glass, causing severe cooling strains. With a tipless lamp, the blowing of the necessary small exhaust hole near the press was a source of weakness and shrinkage.

40 With my improved method, the flare, the inner tube and the leading-in wires are placed in a stem-making machine, and fusion between the tubes caused by the external application of heat and the internal application of air pressure, i. e., after inserting the inner tube and leading-in wires, gas fires or other suitable heating means, are allowed to act on the small end of the flare and an intermediate portion of the inner tube. When a tipless variety of stem is to be made, and the glass is in a plastic state, the inner tube is prevented from closing up by 45 means of air pressure applied within the

inner tube; preferably in the form of a jet of air. The weld or fusion between the two tubes is formed by the surface tension of the glass when in a plastic state assisted by the pressure of the gas fires, if such are used, acting against the air pressure on the inside of the inner tube.

The jet of compressed air directed down the inner tube also serves to cause the stem, which has been formed by this method, to cool from the inside, as well as from the outside, after the fires are withdrawn, thereby reducing cooling strains. A slight expansion of the inner tube at the point of fusing is desirable but not essential and may be regulated by the air jet thus diminishing cooling strains by reducing the thickness of the glass at the point of fusion of the tubes.

45 With a stem of the tipless type, made by this method, the inner tube is used as a combined exhaust tube and arbor. The air to be drawn out of the bulb enters the inner tube from the arbor end, thus making it possible to dispense with the usual small hole located near the stem press. Making the unitary inner tube form both the exhaust tube and arbor, eliminates the handling by the operator of one piece of glass in assembling the parts of a stem in a stem-making machine. As this stem is preferably made up 50 without buttons, the latter being formed during the inserting operation, it is possible to dispense with arbor-making machines.

55 A preferred embodiment of the invention is illustrated in the accompanying drawing, in which,

Fig. 1 is a side elevation of my improved stem after fusing the parts together, a portion being shown broken away;

Fig. 2 shows the parts assembled before applying heat for fusing them together; and,

Fig. 3 illustrates a section on the line III—III of Fig. 1, on a larger scale.

60 In the drawing, 1 represents the usual form of flare which is placed in a suitable fixture for holding the parts in alignment, with the small end preferably extending downwardly. The inner or exhaust tube 2 and conductors or leading-in wires 3 are inserted therein as shown in Fig. 2. The upper portion of the exhaust tube may be held between jaws 10 and 11, the flare tube between jaws 12 and 13 and the lower portion of the exhaust tube between jaws 14 and 15. 65

The lower end of the exhaust tube may be closed by a suitable socket 16 which may be of soft rubber or other material and air may be directed down the exhaust tube from any suitable supply line through a nozzle 17. Heat, preferably in the form of gas fires 18 and 19, is applied to soften the lower or smaller end 21 of the flare and the adjacent portion of the exhaust tube until the flare 10 contracts about the inner tube because of the cohesion and surface tension of the nearly molten glass assisted by the fluid pressure of the gas fires.

Air pressure, preferably in the form of 15 a jet of compressed air, is then applied to the inner tube. This not only prevents the inner tube from closing up, but preferably causes the same to expand slightly against the contracted portion of the flare, as shown 20 at 4, thereby welding the tube and flare together perfectly and also making a perfect seal between the wires and the glass, as shown in Figs. 1 and 3. The air jet may be continued until the glass in the seal solidifies, 25 thereby reducing the usual strains, by cooling more uniformly.

It will readily be seen that, by this method, the stem includes but two pieces of glass, namely, the flare and the inner tube. 30 The usual cane glass arbor is therefore dispensed with, as well as the operation of pressing the glass around the leading-in wires and of consolidating the flare, the exhaust tube and the arbor. In addition, the portion of the 35 inner or exhaust tube, shown in the drawing, downwardly projecting below the seal forms the arbor and, if desired, may have formed thereon one or more buttons.

In exhausting a bulb formed with a stem 40 of this character, the air, instead of being withdrawn from the bulb through a small hole formed near the flare or near the stem press, as in former types of tipless stem construction, is withdrawn through the inner tube forming the arbor. This inner or exhaust tube, therefore, forms the arbor in addition to its usual function and thereby obviates handling three pieces of glass per stem.

50 In making a stem for a lamp of the tipped variety, the usual solid cane arbor may be used and both the inner tube and the jet of air are unnecessary. The seal in this case is formed in much the usual manner, up to the point of mechanical pressing, which is omitted. In the past this pressing operation has been considered essential.

Although this invention is shown embodied in a stem for an incandescent lamp, other 60 applications of its principles are contemplated, as, for instance, in any electrical device employing a vitreous container. It will be apparent, to one skilled in the art, that this method of sealing leading-in wires or other electrodes in glass without the appli-

cation of mechanical force, is of general utility.

While I have illustrated what I now consider to be the preferred embodiment of my invention, it is to be understood that many 70 changes may be effected therein and that my invention is to be limited only by the scope of the appended claims.

What is claimed is:—

1. The method of making incandescent 75 electric lamp stems composed of a relatively small diameter and a relatively large diameter glass tube which comprises supporting the tubes initially spaced apart and substantially in concentric relation, so heating to fuse an end of the outer tube to contract the same about the inner tube and supplying sufficient heat to fuse the inner tube and expanding the fused portions of both the tubes to intimately unite them. 85

2. The method of making incandescent electric lamp stems composed of a relatively small diameter and a relatively large diameter glass tube which comprises supporting the tubes initially spaced apart and substantially in concentric relation, disposing leading-in wires between the tubes, heating to fuse an end of the outer tube to contract the same about the inner tube and supplying sufficient heat to fuse the inner tube and expanding both the fused portions of the tubes to intimately unite them. 90

3. A stem for an incandescent electric lamp comprising a relatively small diameter exhaust tube and a relatively large diameter 100 flare tube, portions of the walls of said tubes being united to constitute a single wall and enlarged to bulbous form interiorly and exteriorly to provide relatively large united portions of said exhaust tube and flare tube. 105

4. A stem for an incandescent electric lamp or other sealed device comprising an exhaust tube of relatively small diameter and a flare tube of relatively large diameter, portions of the walls of said tubes being 110 united and having their united portions shaped to bulbous form interiorly and exteriorly and having a common wall.

5. A stem for an incandescent electric lamp or other sealed device comprising an 115 exhaust tube and a flare tube concentrically arranged and having one end of the flare tube fused to the exhaust tube and shaped to bulbous form both interiorly and exteriorly.

6. A stem for an incandescent electric 120 lamp or other sealed device comprising an exhaust tube and a flare tube concentrically arranged, leading-in wires disposed between said tubes, one end of the flare tube being fused to the exhaust tube, said fused portions having a bulbous shape both interiorly and exteriorly.

7. The method of making tipless incandescent lamp stems which initially include a flare tube of relatively large diameter and

an exhaust tube of relatively small diameter which comprises placing the flare tube around the exhaust tube, disposing leading-in wires in the space between the tubes, applying heat to one end of the flare tube to constrict the same about the exhaust tube whereby the surface tension of the flare tube when nearly molten causes it to contract around the exhaust tube and become fused thereto, maintaining sufficient heat to render the contacting portions of the exhaust tube and flare tube plastic and in applying fluid pressure to work the fused mass and consolidate the tubes with the leading-in wires embedded in the fused portion.

8. The method of making tipless incandescent lamp stems which initially include a flare tube of relatively large diameter and

an exhaust tube of relatively small diameter, which comprises placing the flare tube around the exhaust tube, applying heat to one end of the flare tube, constrict the same about the exhaust tube and permitting the surface tension of the flare when nearly molten to contract around the exhaust tube and unite thereto, maintaining the application of heat to render the flare tube and the contacting portion of the exhaust tube plastic and in applying fluid pressure to expand the heated portions of the tube united in a common wall to attain an effective union of the tubes.

In testimony whereof, I have hereunto subscribed my name this 24th day of March, 1922.

JOHN JOSEPH HIGGINS.
